UNITED STATES PATENT OFFICE.

CARL TRETTAU, OF GIMMEL, GERMANY.

APPARATUS FOR IMPROVING GRAIN.

No. 845,017.

Specification of Letters Patent.

Patented Feb. 19, 1907.

Original application filed October 26, 1905, Serial No. 284,438. Divided and this application filed November 2, 1906. Serial No. 341,679.

To all whom it may concern:

Be it known that I, CARL TRETTAU, a subject of the King of Prussia, residing at Gim-
5 mmel, district Oels, Province of Silesia, and
German Empire, have invented new and use-
ful Improvements in Apparatus for Improv-
ing Grain, of which the following is a specifi-
cation.

The subject of my invention is an appa-
10 ratus for improving wheat, rye, and other
grain with a view to increasing the yield of
flour and improving the quality thereof.

This application is a division of my applica-
15 tion, Serial No. 284,438, filed October 26,
1905.

Hitherto it has been the practice to clean
20 the grain in cylindrical dust-removers, so-
called "aspirators," separators, and other
cleaning and hulling and like machinery, and
then to wash it in special apparatus and
finally dry it. The yield of flour and the
25 quality thereof depends upon the thorough-
ness with which the cleansing is carried on.

By means of the new apparatus grain can
25 be perfectly cleaned either in its natural or
granular form or after having been coarsely
crushed or triturated, whether uncleansed or
30 after being submitted to a preliminary clean-
ing, by a current of air which after being
highly heated is conducted into the grain
35 with the aid of a suitable suction or force
pump, ventilator, or the like. The heating
of the air may be best effected by electric
arcs through or past which the air flows;
but any other suitable flame for producing
40 the same effect may be employed. The air
may be conducted to the grain either in hot
condition or after being cooled down.

By means of the electric arcs or the like
45 any pathogenic bacteria and germs present
in the air will be destroyed. The air is itself
rendered actually germicidal, and it retains
this character even though it may be greatly
cooled down. These impurities in the grain,
50 which, as above remarked, cannot be got rid
of with cleaning machinery and washing appa-
ratus as commonly employed, are thor-
oughly removed by means of the treatment
of the grain in the new apparatus with the
55 active and purifying current of air. Impuri-
ties—such as bacteria, fungi, and more highly-
organized animalcules, which adhere particu-
larly in the fissure and pores of the cuticle—
are absolutely destroyed.

55 The treatment of the grain with the active

and purifying air will naturally be the more
complete the more carefully the preliminary
clearing has been effected. The new appa-
ratus, however, has been found extremely ef-
ficient even in the case of uncleansed grain. 60
The treatment of the grain with the active
and purifying air is effected by introducing
the air into one or several of the cleaning-
machines through which the grain travels for
clearing purposes or into any of the appara- 65
tuses for transporting the grain from one ma-
chine to another either in granular form or in
a coarsely-crushed state.

In the case of grain submitted to a prelimi-
nary washing the present apparatus can be 70
successfully employed in place of special dry-
ing-machines at present in use for getting rid
of the moisture. In the old machines, which
are particularly in use with soft wheat, the
current of air employed for drying is heated 75
by a coke-fire or by means of pipes heated by
steam. Such apparatuses, however, are trou-
blesome to manage and expensive in use and
are more or less dependent upon the mois-
ture in the air. With wet air it is almost 80
impossible to obtain really well-dried grain.

Air treated in the new apparatus is admir-
ably adapted for drying washed grain, so
that drying apparatuses such as are at pres-
ent in use are rendered altogether superflu- 85
ous. Thus when washed grain is treated
with the active purifying air-current not only
will the corn be thoroughly dried, but it will
at the same time be perfectly cleaned.

My invention is illustrated in the drawing, 90
in which the figure is an elevation of one form
of the new apparatus.

a is a pipe having apertures at *b*, above
which arc-lamps *c* are disposed. One end of
the pipe *a* is closed, while the other end is 95
connected with the ventilator *d*, which causes
the air to flow past the arcs into and through
the pipe *a* to the places of work—*i. e.*, clean-
ing-machine, transporting device, or grind-
ing apparatus. 100

What I do claim as my invention, and de-
sire to secure by Letters Patent, is—

1. Apparatus for treating grain with a cur-
rent of air, comprising a perforated duct,
flame heating means located at the apertures
thereof, and means for causing a current of
air to pass through the apertures and along
the duct and to the grain to be treated, sub-
stantially as described. 105

2. Apparatus for treating grain with a cur- 110

rent of air, comprising a perforated duct, electric-arc lamps located at the apertures thereof, and a ventilator for sucking a current of air through the apertures and along the duct and delivering it to the grain to be treated, substantially as described.

5 In testimony whereof I have signed my

name to this specification in the presence of two subscribing witnesses.

CARL TRETTAU.
